(57) CLAIM

The ornamental design for a combined extendable deck and awning for a recreational vehicle, as shown and described.

DESCRIPTION

FIG. 1 is a rear view of a combined extendable deck and awning for a recreational vehicle, showing our new design.

FIG. 2 is a front view thereof;

FIG. 3 is a right-side view thereof;

FIG. 4 is a left-side view thereof;

FIG. 5 is a top view thereof;

FIG. 6 is a front, left side perspective view thereof;

FIG. 7 is a front, right side perspective view thereof;

FIG. 8 is a rear, right side perspective view thereof; and,

FIG. 9 is a front, left side perspective view thereof.

The broken lines in the drawings depict parts of the combined extendable deck and awning for a recreational vehicle that form no part of the claimed design. The broken lines in the figures also illustrate environmental subject matter and other features that form no portion of the claimed design.
